(Cl. D52—1)

To all whom it may concern:

Be it known that we, Ralph M. Rowell and Roger B. Kerr, citizens of the United States, residing respectively at Lynn, in the county of Essex, Commonwealth of Massachusetts, and at Jamestown, county of Newport, State of Rhode Island, have invented a new, original, and ornamental Design for an Instrument Case, of which the following is a specification, reference being had to the accompanying drawing, forming a part thereof.

Fig. 1 is a front perspective view of an instrument case showing our new design;

Fig. 2 is a side elevational view; and

Fig. 3 is a top plan view.

We claim:

The ornamental design for an instrument case, as shown.

RALPH M. ROWELL.
ROGER B. KERR.
